GRAPH PLOTTER

Eugene Seid and Robert Charles Morton, Inglewood,
Calif., assignors to California Computer Products, Inc.,
Downey, Calif., a corporation of California

Filed Feb. 10, 1960, Ser. No. 59,337

Term of patent 14 years

(Cl. D26—14)

Figure 1 is a front perspective view of a graph plotter, showing our new design;

Figure 2 is a side elevational view of the plotter of Figure 1, on a reduced scale, the opposite side of the plotter being substantially a mirror image of this view; and

Figure 3 is a rear elevational view thereof, to a reduced scale.

We claim:

The ornamental design for a graph plotter, substantially as shown and described.
